ATTORNEY

UNITED STATES PATENT OFFICE.

LOUIS SAINBERG, OF NEW YORK, N. Y.

DESK-PAD.

1,285,401.

Specification of Letters Patent. Patented Nov. 19, 1918.

Application filed June 24, 1918. Serial No. 241,646.

To all whom it may concern:

Be it known that I, Louis SAINBERG, a citizen of the United States, and a resident of New York, in the county of New York and State of New York, have invented a certain new and useful Improvement in Desk-Pads, of which the following is a full, clear, and exact specification.

This invention relates to a class of devices adapted to be used especially on desks.

My invention has for its objects primarily to provide a pad designed to be employed for permitting especially glass plates to be used on tops of desks, tables and elsewhere whereby writing surfaces may be provided as well as allowing blotters to be used between the plate and the pad for convenient utilization if desired. The invention resides mainly in providing a fast flexible cushion so that when arranged on the top of a desk or table it will conform with any unevenness of the top, besides serving to yieldingly hold a plate of glass or the like. On the edge of the cushion may be a suitable number of spring actuated retainers adapted to engage the plate when disposed thereon, in order to removably and hingedly hold the plate against accidental movement on the cushion.

A further object of the invention is to provide a desk pad of a simple and efficient construction which may be made in any desired size and shape.

A practical embodiment of the invention is represented in the accompanying drawing forming a part of this specification in which similar characters of reference indicate corresponding parts in all the views, the said invention being more fully described hereinafter, and then pointed out in the claims at the end of the description.

In the drawing, Figure 1 is a perspective view, partly broken away, of one form of desk pad embodying my invention.

Fig. 2 is a perspective view of the pad with its glass plate removed, and which shows one corner of one of the members of the cushion of the pad separated from a corner of the other member.

Fig. 3 is an enlarged fragmentary sectional view taken on the line 3—3 of Fig. 1, and

Fig. 4 is an enlarged perspective view of one of the retainers used in the device.

The device has a flexible cushion 10 which may be of any desired shape, though the cushion is preferably substantially rectangular

as well as being of a suitable size for use on the top of a desk, or table and elsewhere. The cushion 10 may be composed of one or a number of superimposed members, as 11 and 12, both of which are similar in formation. Each member of the cushion may be made of a sheet of cardboard, or binder's board or other material of a firm flexible quality to serve, as a stiffener 13, and each of these flexible stiffeners has a covering 14 of cloth or other flexible fibrous material. The covering 14 of the stiffener 13 of each member of the cushion may be of sufficient size to completely embrace both surfaces of each stiffener, or the cover may be of a size so that one surface of each stiffener besides its marginal edge part are covered. This is accomplished by making each covering of a shape to allow of being arranged upon one surface of its respective stiffener, after which the marginal edge parts of the covering are disposed in overlapping arrangement over the edge of the stiffener and on the other surface of the stiffener so as to cover the desired portion of the second surface of the stiffener. The marginal edge parts of each covering are then cemented or glued to its stiffener, as at 15, and the cushion 10 is provided by sealing or cementing together the second entirely covered or partially covered surfaces of both of the flexible stiffeners 13. The cushion thus made is in the form of a substantially rectangular flexible pad so that it will conform with any unevenness of the top of a desk or table or the like.

Removably and hingedly held on the cushion or pad 10 is a plate 16 of glass or other material to provide a suitable surface for writing purposes. The glass plate 16 is preferably of a shape corresponding to the shape of the cushion 10 as well as being of a size slightly smaller than the cushion, and in practice I prefer to employ a glass plate of unusual thickness so as to avoid being easily broken. The cushion 10 being made, as above described, also serves for protecting the glass plate against damage by yieldingly supporting the plate on the desk or table.

In order to removably and hingedly hold the glass plate on the cushion or pad 10 one or a number of retainers, as 17 and 18, are provided. These retainers are similarly formed and may be of any desired types, though each retainer is preferably formed

of a strip spring metal of a desired length and width. Each of the retainers 17 and 18 is fashioned by an end portion of the strip being transversely bent, as at 19, to provide 5 a tongue or base plate 20, and through this base plate of each retainer are a number of spaced openings, as 21, 22, 23. Part of each strip in spaced relation to the base plate 19 is then transversely bent, as at 24, to 10 provide a wall 25 disposed rightangularly with respect to the base plate 20, besides providing a finger or clamping jaw, as 26, which is arranged in spaced relation to the base plate. The wall 25 of each retainer is 15 somewhat wider than the thickness of the glass plate 16, while the free end part of the clamping jaw 26 of each retainer is curved downwardly toward the apertured base plate 20 to a distance somewhat less than 20 the thickness of the glass plate.

The spring retainers 17 and 18 are applied to the cushion 10 at spaced intervals on one of the lengthwise edges of the cushion so that the walls 25 of the retainers extend upwardly from one face of the cushion and so that the clamping jaw 26 overhangs the cushion as well as being spaced from the cushion. The retainers are secured to the cushion by the base plates 20 being inserted 25 between the members 11 and 12 of the cushion when these members are assembled, and by cementing or gluing or otherwise fastening the base plates between the members of the cushion during the cementation of the members, as herein before explained, the retainers will be tightly held to the cushion, the openings 21, 22, 23 of the base plates being provided to allow the cement to be received therethrough to effectually hold the 30 plates to the members as without openings in the plates the cement would not properly adhere to the plates. By this manner of associating the retainers with the cushion the glass plate 16 is applied on the cushion 35 by one of its lengthwise edge parts being disposed under the clamping jaws 26 of the retainers and if desired a sheet of blotting paper, as 27 may be arranged between the glass plate and the cushion for ready use 40 by reason of the glass plate being removably as well as hingedly held on the cushion.

In the foregoing description, I have embodied the preferred form of my invention, but I do not wish to be understood as limiting myself thereto, as I am aware that modi- 45

fications may be made therein without departing from the principle or sacrificing any of the advantages of this invention, therefore I reserve to myself the right to make such changes as fairly fall within the scope 50 thereof.

Having thus described my invention, I claim as new and desire to secure by Letters Patent:—

1. A device of the character described, 65 comprising a flexible yielding pad and spring actuated retainers on the edge of the pad for yieldingly engaging one edge of a transparent plate whereby the plate will be removably as well as hingedly held to the 70 pad.

2. A device of the character described, comprising a substantially rectangular cushion, and spaced spring actuated retainers on one edge of the cushion for yieldingly engaging one edge of a transparent plate whereby the plate will be removably as well as hingedly held to the cushion. 75

3. A device of the character described, comprising a flexible yielding pad, a substantially rectangular transparent plate on the pad, and a plurality of spaced clamping fingers on one edge of the pad as well as overhanging the pad for receiving one edge of a transparent plate whereby the plate will 80 be removably as well as hingedly held to the pad. 85

4. A device of the character described, comprising a substantially rectangular cushion, and a plurality of spaced clamping fingers on one edge of the cushion as well as overhanging the cushion for receiving one edge of a transparent plate whereby the plate will 90 be removably as well as hingedly held to the cushion. 95

5. A device of the character described, comprising a substantially rectangular pad composed of superimposed flexible members, a substantially rectangular transparent plate on the pad, and two spaced yielding fingers protruding upwardly from one edge of the pad and overlapping the plate in engagement with the plate whereby the plate is removably as well as hingedly held on the pad. 100

This specification signed and witnessed 105 this 22nd day of June A. D. 1918.

LOUIS SAINBERG.
